ENCLOSURE FOR SWITCHING EQUIPMENT AND THE LIKE

James B. McClure, 7810 Scenic Drive,
Kansas City, Mo. 64152

Filed Apr. 15, 1974, Ser. No. 460,828

Term of patent 14 years

Int. Cl. D13—03

U.S. Cl. D26—13 C

Fig. 1.

Fig. 2.

Fig. 3.

Fig. 4.

Fig. 5.

Fig. 6.

FIG. 1 is a front elevational view of the design for enclosure for switching equipment and the like, the broken lines indicating a ground line.

FIG. 2 is a side elevational view of the design of FIG. 1. The opposite side is identical.

FIG. 3 is a rear elevational view of the design of FIG. 1.

FIG. 4 is a top plan view of the design of FIG. 1.

FIG. 5 is a front elevational view of a modified form of the design of FIG. 1, the broken lines indicating a slab resting on the ground.

FIG. 6 is a side elevational view of the modified form of the design of FIG. 5. The side opposite is identical.

The broken lines in FIGS. 1, 2, 3, 5 and 6 are for illustrative purposes only.

I claim:

The ornamental design for an enclosure for switching equipment and the like, as shown and described.
